(57) **CLAIM**

The ornamental design for a buckle component, as shown and described.

DESCRIPTION

FIG. 1 is a top plan view of a buckle component showing my new design;

FIG. 2 is a bottom plan view thereof;

FIG. 3 is a top perspective view thereof;

FIG. 4 is a right side view thereof;

FIG. 5 is a left side view thereof;

FIG. 6 is a front view thereof;

FIG. 7 is a rear view thereof; and,

FIG. 8 is a bottom perspective view thereof.

Broken lines show portions of the buckle component which form no part of the claimed design.
